CLAIM

The ornamental design for eyewear frames, as shown and described.

DESCRIPTION

FIG. 1 is a perspective view of eyewear frames;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view of the eyewear frames of FIG. 2 taken across line 8-8.

The broken lines shown represent unclaimed subject matter and form no part of the claimed design.
